ATTORNEY.

UNITED STATES PATENT OFFICE.

KONSTANTY KOZTOWSKI, OF ROCKWOOD, PENNSYLVANIA.

DESIGN FOR A CHAIN ORNAMENT.

59,493.

Specification for Design.

Patented Oct. 25, 1921.

Application filed April 12, 1921. Serial No. 460,817. Term of patent 7 years.

To all whom it may concern:

Be it known that I, KONSTANTY KOZTOWSKI, a citizen of Poland, residing at Rockwood, in the county of Somerset and State of Pennsylvania, have invented a new, original, and ornamental Design for a Chain Ornament, of which the following is a specification, reference being had to the accompanying drawing, forming part thereof.

The figure is a face view of a chain ornament constituting my new design.

I claim:

The ornamental design for a chain ornament as shown.

KONSTANTY KOZTOWSKI.
